WOOD CARRIER

George L. Woods, Franklin, Mass., assignor to S. M. Howes, Inc., Fall River, Mass., a corporation of Massachusetts

Filed May 1, 1961, Ser. No. 64,978

Term of patent 14 years

(Cl. D81—18)

FIG. 1 is a side elevational view of a wood carrier, showing my new design;

FIG. 2 is a top plan view thereof on a reduced scale;

FIG. 3 is a bottom plan view thereof on a reduced scale;

FIG. 4 is a front elevational view thereof;

FIG. 5 is an enlarged fragmentary view of the ornamental detail around the peripheral edge thereof; and

FIG. 6 is a fragmentary sectional view taken on line 6-6 of FIG. 5.

It is understood that the ornamentation is extended around the entire peripheral edge as indicated by the broken lines in FIGS. 1, 2 and 3.

The characteristic feature of my design for the wood carrier disclosed resides in the ornamental details around the peripheral edge of the carrier, as best shown in FIGS. 1, 5 and 6.

I claim:

The ornamental design for a wood carrier, substantially as shown and described.
